Primary Examiner — Katherine Glennon(74) Attorney, Agent, or Firm — Fox Rothschild LLP(57) CLAIM

The ornamental design for a watch, as shown and described.

DESCRIPTION

FIG. 1 is a perspective view of a watch according to the design;
 FIG. 2 is a top view thereof;

FIG. 3 is a bottom view thereof;

FIG. 4 is a front view thereof;

FIG. 5 is a right side view thereof;

FIG. 6 is a left side view thereof; and,

FIG. 7 is a back side view thereof.

The broken lines depict portions of the watch that form no part of the claimed design.

1 Claim, 7 Drawing Sheets(56)
